UNITED STATES PATENT OFFICE.

JAMES TOTHAM, OF NEW HAVEN, CONNECTICUT, ASSIGNOR OF ONE-HALF
TO JOHN M. PECK, OF SAME PLACE.

COUPLING FOR WATER-CLOSETS.

SPECIFICATION forming part of Letters Patent No. 568,996, dated October 6, 1896.

Application filed May 28, 1896. Serial No. 593,484. (No model.)

To all whom it may concern:

Be it known that I, JAMES TOTHAM, of New Haven, in the county of New Haven and State of Connecticut, have invented a new Improvement 5 in Couplings for Water-Closets; and I do hereby declare the following, when taken in connection with the accompanying drawings and the letters of reference marked thereon, to be a full, clear, and exact description 10 of the same, and which said drawings constitute part of this specification, and represent, in—

Figure 1, a view in side elevation of a coupling constructed in accordance with my invention; Fig. 2, a view thereof in vertical central longitudinal section; Fig. 3, a detached plan view of the rubber coupling-pipe; Fig. 4, a view in vertical transverse section on the line *a b* of Fig. 2; Fig. 5, a view in end 15 elevation of the spud-collar, looking at the outer end thereof; Fig. 6, a face view of the neck of the closet-bowl; Fig. 7, a detached plan view of the coupling-plate; Fig. 8, a similar view thereof in inside elevation.

My invention relates to an improvement in the couplings employed between water-closet bowls and the flush-pipes thereof, the object 20 being to produce a simple, durable, and convenient coupling which will accommodate it self to any changes in the relative positions 25 of the bowl and pipe due, for instance, to the settling of the building containing the plumbing.

With these ends in view my invention consists in a self-adjusting coupling having certain details of construction and combinations of parts, as will be hereinafter described, and pointed out in the claim.

In carrying out my invention I employ a 30 short coupling-pipe *A*, made of india-rubber and therefore flexible and self-accommodating to the relative positions of the parts with which it is connected. The inner end of the said pipe is formed with a flange *A'*, adapted 35 to occupy and pack an annular recess *B*, formed in the neck *B'*, which is by preference molded integral with the earthenware closet-bowl *B''*, which may of course be of any approved construction. The horizontally-arranged central passage *B³* of the neck opens 40 into the bowl and discharges thereinto the

water brought to the bowl by the flush-pipe. The coupling-pipe *A* is also formed near its inner end with a large annular flange *A²*, designed to bear directly against the flat outer 55 end of the neck *B'*, as clearly shown in Fig. 2, whereby a large bearing between the pipe and neck is secured. The said flange is held against the end of the neck by means of a coupling-plate *C*, provided at its respective 60 ends with ears *C' C'*, having perforations for the reception of screw-bolts *D D*, furnished at their outer ends with nuts *D' D'* and provided at their inner ends with heads *D² D²*, which are engaged with the inner faces of the 65 ears *B³ B³*, extending in opposite directions from and formed integral with the neck *B'*, the said ears being formed with open slots *B⁴ B⁴* for the reception of the shank portions of the screw-bolts, by means of which the coupling-plate is drawn against the flange *A²* and 70 the same pressed against the end of the neck *B'*.

The inner face of the coupling-plate is constructed with an annular recess *C²* for the reception of the flange *A²*, as shown in Fig. 2. The rubber coupling-pipe *A* is also constructed adjacent to the outer face of the flange *A²* with an exterior annular bead *A³*, which fits 75 into a cavity *C³*, formed in the coupling-plate *C*, and enlarging the grip of the plate upon the rubber pipe and additionally providing 80 against any leakage from the pipe in case it is markedly flexed by such a settling of the building as to disturb the relations of the bowl 85 and flush-pipe.

The outer portion of the pipe *A* receives the externally-threaded collar *E*, which, as it corresponds in function to the spud ordinarily inserted directly into the neck of a water-closet bowl, I shall term the "spud-collar." This is furnished at its inner end with a faceted flange *E'*, adapting it to be grasped and held against rotation by a wrench or equivalent tool. The said spud-collar is held 90 against rotation upon the rubber pipe *A* by its provision with two grooves *E² E²*, leading out of its central opening and designed to receive ribs *A⁴ A⁴*, formed upon the exterior surface of the pipe, as clearly shown in Fig. 4. 95

The extreme outer end of the pipe *A* is formed with an outwardly-extending annular

flange A⁵, which, when the parts are assembled, engages directly with the outer edge of the spud-collar, as shown in Fig. 2, the said flange being forced against the said end of the collar for packing the same by means of a flange F, formed upon the inner end of the flush-pipe elbow F', the flange F of the elbow F' being forced against the flange A⁵ of the rubber pipe A by means of a coupling-collar G, which is externally threaded to take into the external threads of the spud-collar, as clearly seen in Fig. 2.

It will be seen by an inspection of the drawings that when my improved coupling is in use the rubber pipe is firmly held by each end, while its central portion is concealed and protected. At the same time there is sufficient play provided for between the metal parts to permit the rubber pipe to flex, and so to accommodate the coupling to any changes in positions of the bowl and flush-pipe due, for instance, to the settling of the building, &c.

It is apparent that in carrying out my invention some changes from the construction herein shown and described may be made, and I would therefore have it understood that I do not limit myself to the exact construction herein shown, but hold myself at liberty to make such changes and alterations as fairly fall within the spirit and scope of my invention.

Having fully described my invention, what

I claim as new, and desire to secure by Letters Patent, is—

In a self-adjusting coupling for water-closet bowls and flush-pipes, the combination with a bowl provided with a neck, of a rubber coupling-pipe adapted at its inner end to be inserted into the outer end of the neck, and formed at its outer and its inner ends with outwardly-projecting annular flanges, of a coupling-plate adapted to be connected with the bowl, and to be engaged with the flange at the inner end of the pipe for pressing the same against the neck, an externally-threaded spud-collar located upon the outer portion of the rubber coupling-pipe and arranged to be non-rotatable thereupon, and to have its outer end engaged by the flange formed at the outer end of the pipe, an elbow-coupling provided with a flange engaging with the flange at the outer end of the pipe, and a coupling-collar holding the flanged end of the elbow-coupling against the flanged outer end of the pipe, and engaging with the spud-collar, substantially as set forth.

In testimony whereof I have signed this specification in the presence of two subscribing witnesses.

JAMES TOTHAM.
